UNITED STATES PATENT OFFICE.

THOMAS E. GRIFFIN, OF WEST HAVEN, CONNECTICUT.

TOY.

Application filed August 16, 1926 Serial No. 129,552.

The invention relates to improvements in a novelty or toy.

It is an object of the invention to provide a toy that may represent in outline a duckling or the like and which when moved over a surface, will present a walking or waddling movement simulating the natural walking movement of a duck.

My invention is base on the discovery that if a toy is constructed with a certain formed base and is provided with a pair of lateral fins or projections, that friction and gravitation will cause the article to rock from side to side and to have a forward and backward movement in conjunction with said side to side motion. I have found that in using a rounded base in conjunction with the lateral web or feet that when the article is drawn over a surface this uniform waddling movement is effected, due to the swinging of the toy from side to side by gravity and friction and the contact of the feet or the fins with the floor surface.

In the accompanying drawings, I have shown the toy as representing a duck which naturally has the waddling motion which is obtained when this toy is moved over a floor surface. It will be understood, however, that the toy may represent other fowl or animals where it is desired to simulate their walking motion.

In the drawings,

Fig. 1 designates a view of the device,

Fig. 2 is a view where the toy represents its central position,

Fig. 3 is a view where the toy has swung to the left with its left foot or fin in engagement with the floor surface,

Fig. 4 is a view where the right-hand side of the toy has swung down with the right fin or foot in contact with the floor surface, and

Fig. 5 is a view showing the left-hand side of the toy in a rear position and the right-hand side in a forward position, while Fig. 6 reverses the position shown in Fig. 5.

Figures 7 and 8 illustrate a modified form of my invention.

Referring now more particularly to the drawings, wherein like reference characters indicate corresponding parts, the numeral 1 designates the base of the toy. As clearly shown, this base is at its bottom rounded so as to be free to rock from one side to the other. The toy, however, is so constructed

that when it is idle it will maintain a position such as shown in Fig. 2, that is to say, it is well balanced.

The toy naturally has a neck and head. In the embodiment of the invention herein shown, the top in its entirety resembles a duck, although it may, in keeping with the desire of the maker, resemble other fowls or animals.

Near the rear end of the toy, feet or fins 3 and 4 project laterally therefrom. These fins or feet are preferably of a flexible material and, as shown at their outer ends, are widened to provide floor engaging surfaces of a substantial contour. The feet or fins 70 project from the body near the rear end thereof.

In Figs. 7 and 8 of the drawings, I have shown a modified form of the invention in which a roller 8 is inserted in the base of 75 the toy. Otherwise, the structure is the same as the base is rounded, and the toy balanced so that the slightest friction will throw the toy from one side to the other.

In both the preferred and modified form 80 of the invention, the toy is preferably constructed so as to have a base presenting a rubber surface. Any other materials may be used which will offer some resistance to the advancing movement of the toy over 85 the floor surface.

It is an object of this invention to provide a toy, which, when moved by the string 9 over a surface of wood, glass, carpet, or the like, presents a waddling movement simulating the walking movement of a duck. This is caused by disturbing the equilibrium of the toy due to friction and gravity. When the toy is pulled over the surface, as shown in Fig. 2, the left-hand side will rock or move downwardly while swinging in a forward direction until the foot or fin 3 engages the floor surface. This contact of the foot or fin with the floor surface, while the toy is being dragged, causes the toy to 100 swing or rock to the position shown in Fig. 4 at which time the foot or fin 4 swings downwardly and coacts with the floor surface. When the rocking movement of the toy is as just described, the left-hand side 105 of the toy with its fin 3 also slightly moves forwardly. Such motion is fully shown in Figs. 5 and 6. The uniform waddling or walking movement of the toy is effected by reason of the friction offered to the move- 110

ment of its rounded base over the surface, disturbing the gravity of the toy and the feet or fins which alternately cause the body to rock from right to left and at the same time to swing in forward and reverse directions such as clearly shown in Figs. 5 and 6.

While I have shown the toy as representing a duck, it may, of course, represent other objects and, in fact, any object which it is desirable to pull across a surface and have present a walking or waddling movement.

Having thus described my invention, what I claim is:

1. A toy comprising a body having a floor engaging surface rounded to permit substantially universal rocking movement and a plurality of laterally extending members secured to the lower portion of said body and adapted for engagement with the floor when said body is rocked laterally and means for advancing the toy over the floor.

2. A toy comprising a body having a substantially parti-spherical bottom surface for engagement with a supporting medium such as a floor or the like and a lateral projection on each side of said body adjacent the lower portion thereof and means whereby the toy may be advanced over said supporting medium.

3. A toy comprising a body having a base portion formed with a substantially parti-spherical contacting surface for engagement with a supporting medium and a member secured to and projecting from each side of said body adjacent to said contacting surface portion but out of engagement with the supporting medium in the normal upright position of the toy and means whereby the toy may be advanced over said supporting medium.

4. A toy of the character described comprising a substantially semi-spherical body portion and a plurality of projections extending laterally therefrom adjacent the lower portion thereof and spaced from but adapted for engagement with a supporting surface upon rocking movement of said body portion and means for advancing the toy over the supporting surface.

5. A toy of the character described comprising a body portion, a figure-head secured

to said body portion, a base secured to said body portion and having a substantially parti-spherical floor contacting surface, a pair of fins projecting from said base, one at each side thereof, and adjacent the said contacting surface, whereby when said toy is drawn across a floor or the like it will automatically oscillate about both its longitudinal and vertical axes and means for drawing the toy across the floor or the like.

6. A toy having a base provided with a substantially parti-spherical floor engaging surface and a lateral fin projecting from said base at each side thereof and adjacent to but spaced vertically above said surface for the purpose described and means whereby the toy may be moved across a floor or the like.

7. A toy of the character described comprising a body having a substantially parti-spherical base, said base being balanced to normally maintain the toy in a substantially upright position, a pair of fins projecting one from each side of the toy at the rear of the base and adjacent to but above its point of surface contact, and means for drawing the toy over a surface whereby it alternately rocks from one side to the other while the lateral fins move alternately in a back and forth direction.

8. A toy of the character described comprising an elongated body portion, a substantially semi-spherical base secured to said body portion, a figure-head secured to the top of said body portion adjacent the forward edge thereof, a pair of frictional floor engaging members secured to said base adjacent the body and projecting one from each side thereof and means secured to said body in substantial alinement with its longitudinal axis for attachment of a pull cord or the like.

9. A toy constructed substantially in accordance with claim 3 and wherein said members are formed of flexible material.

10. A toy constructed substantially in accordance with claim 3 and wherein the contact surface of said base and the said projecting members are formed of friction material and said members are flexible.

In testimony whereof I affix my signature.
THOMAS E. GRIFFIN.
